L. R. PORTS

MOVING DISPLAY SIGN

Filed Aug. 24, 1925

UNITED STATES PATENT OFFICE.

LOUISE R. PORTS, OF TROUTDALE, OREGON.

MOVING DISPLAY SIGN.

Application filed August 24, 1925. Serial No. 52,113.

My invention relates to improvements in electric lighted signs of the hanging type, adapted for use in places of business, where-
in the sign may be displayed above the side-
walk or entrance.

One of the objects of my moving display sign, consists in having an electric lighted display, located at either side of the sign, adapted to having a stationary sign dis-
played therein and having a revolvable car-
rying member disposed centrally of the main frame structure, having electric lighted signs mounted upon supports adapt-
ed to be rotated so that the signs appear
for a short period of time, disposed below
the main sign structure.

A further object of my invention, con-
sists in having means of renewing the sign
adapted to being maintained within the
revolvable member without in any way dis-
mantling the sign.

A further object of my invention, con-
sists in new and novel means of constructing
the same, of few parts and one that may
be easily operated by those unskilled in
mechanical matters.

With these and incidental objects in view,
the invention consists in certain novel fea-
tures of construction and combination of
parts, the essential elements of which are
set forth in the appended claims and to a
preferred form of embodiment of which is
hereinafter shown with reference to the
drawings which accompany and form a part
of this specification.

In the drawings:—

Fig. 1 is a side elevation of my assembled
device.

Fig. 2 is a side elevation, partially in sec-
tion, with one of the side closures removed
to better illustrate the construction of the
same, the same being taken on line 2—2 of
Fig. 3, looking in the direction indicated.

Fig. 3 is an end view of the mechanism
shown in Fig. 2, taken on line 3—3, looking
in the direction indicated.

Fig. 4 is a fragmentary, side elevation,
illustrating the means of supporting one of
the units of the signs being carried on the
member being rotated longitudinally of the
device.

Fig. 5 is an end view of one of the mov-
able units.

Fig. 6 is a side elevation of one of the
sign members shown removed. 55

Like reference characters refer to like
parts throughout the several views.

1 is the case of the device which is adapt-
ed to be maintained in position through
suitable hanging brackets 2, disposed upon
the outer wall surface of the same. Located
at either side of the frame device, are side
closures 3 and 4, having disposed therebe-
hind, inner wall members 5 and 6, and
spaced apart from the outer walls. The
wall members 5 and 6, will be of suitable
color to reflect the lights 7, 8, 9 and 10, lo-
cated between the inner and outer wall mem-
bers. The outer wall members will be cut
out and have openings therethrough, as
shown at 11, as properly advertising the
business of the merchant using the same.
These letters may be made of any suitable
size, or shape, to properly display the busi-
ness of the owner thereof. A longitudinal
bearing shaft 12, is located centrally of the
main case and housed within suitable bear-
ings 13 and 14, for maintaining the same
therein. Disposed about this shaft is a driv-
ing pulley 15, adapted to receive the belt 16,
of the prime mover 17, as an electric motor,
having electric outlets 18, to a source of
electric energy for operating the same. The
main central shaft is adapted to support a
radially armed hub or spider, as shown at
19 and 20, one of which is disposed upon
each of the opposite ends of the central
shaft. Members 19 and 20 have arms dis-
posed thereupon. The number and character
of the arms depend upon the size and mag-
nitude of the sign. I have here shown the
same as carrying four arms upon each.
These arms as assembled upon the central
shaft, are so arranged that the arms of each
end are opposite each other in order that the
moving sign to be maintained therebetween
will be held in alignment. The moving sign
member 21, is made of side, top, bottom and
end walls, and the end walls have disposed
thereupon suitable bearing supports 22 and
23, through which the electric illuminating
current passes. The current is led into the
sign through the conduit 35, into the collec-
tor ring 36, secured to the pulley 15. The
ring 38 and the radially armed hub are 100
mounted upon the shaft having an insulating

sleeve 37, disposed between the hub and the shaft to prevent the flow of electric current through the central shaft. A suitable conduit 23^a connects the inlet through the arm of the hub into the electric lamp socket 26, having electric lamps 27, secured thereto. The size and number of the electric lamps to be placed within the secondary sign units will depend upon the size of the same. The circuit is completed by passing the same through the conductor 24, and the terminal pin 25, into the bearing support 23. The bearing support 23 is mounted upon a suitable journal pin 28, disposed within the outer ends of the arms of the spider, the same being in threaded relation with the arm and the same may be further held in working relation therewith through the action of the thumb wing nut 29, and the set screw 31. The secondary rotatable sign members are made of side and end walls adapted to be suspended between the spider arms and to be illuminated through the medium of the electric lamps hereinabove referred to and since the same are journaled above the center of gravity and are held in free turning relationship with the pin supports they will be maintained in an upright position. The ends may be slotted as shown at 32, and 33, to permit the insertion of stenciled plates 34 therein and which may be easily removed and ones carrying a different design or notice be mounted therein. The electric current circuit is completed by the same passing out through the collector ring 38 mounted upon the insulated bushing 37, between the ring and the supporting shaft and thence to the outlet 39, which acts as a ground for the circuit by being connected to a ground source.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow:

What I claim is:

1. A moving display sign, comprising a bottomless case structure having parallel inner and outer side walls; a longitudinal shaft rotatably mounted in said case structure, hubs, having oppositely positioned arms, mounted on said shaft, sign members pivotally mounted on said oppositely positioned arms, said sign members during the rotation of said shaft, passing in and out said case structure, through the bottom there-

of; said sign members having parallel illuminable side walls, and electric circuit means to illuminate said sign members.

2. A moving display sign, comprising a bottomless case structure having parallel inner and outer side walls, a longitudinal shaft rotatably mounted in said case structure; hubs, having oppositely positioned arms, mounted on said shaft, journal pin bearing supports threaded through the outer ends of said arms and parallel to said shaft; sign members mounted at the outer ends of said oppositely disposed arms, said sign members having illuminable side walls, bearing supports mounted at the outer ends of said sign members, adjacent the tops thereof, and engaging with said journal pin bearings, said sign members during the rotation of said shaft, passing in and out said case structure, through the bottom thereof; electric lamps mounted in said sign members, and there being means to conduct an electric circuit through said arms and within said sign members to illuminate said electric lamps.

3. A moving display sign, comprising a bottomless case structure having parallel inner and outer side walls, bracket supports secured to the top of said case, a longitudinal shaft rotatably mounted in said case structure, there being a prime mover in said case to rotate said shaft, hubs having outwardly disposed arms mounted on said shaft, the arms of one hub being positioned opposite the arms of the other hub; journal pin bearing supports threaded through the outer ends of said arms and parallel to said shaft; sign members, comprising, top, bottom, sides, and end members, mounted to the outer ends of said oppositely disposed arms, said sign members during the rotation of said shaft, passing in and out said case structure, through the bottom thereof; said sign members having illuminable side walls, there being slots provided in the ends of said sign members for the insertion and removal of sign plates; bearing supports mounted at the outer ends of said sign members and adjacent the tops thereof; said bearing supports to engage with said journal pin bearings, said sign members during a portion of their rotation about a common axis passing to a point below and exterior of the case structure; electric lamps mounted in said sign members, and there being means to conduct an electric circuit through said arms and within said sign members to illuminate said electric lamps.

LOUISE R. PORTS
